F. M. FURBER.
BURNISHING MACHINE.
APPLICATION FILED AUG. 5, 1918.

1,404,196.

Patented Jan. 24, 1922.

INVENTOR
Frederick M. Furber

UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

BURNISHING MACHINE.

1,404,196.

Specification of Letters Patent. Patented Jan. 24, 1922.

Application filed August 5, 1918. Serial No. 248,345.

To all whom it may concern:

Be it known that I, FREDERICK M. FURBER, a citizen of the United States, residing at Revere, in the county of Suffolk and 5 State of Massachusetts, have invented certain Improvements in Burnishing Machines, of which the following description, in connection with the accompanying drawings, is a specification, like reference characters 10 on the drawings indicating like parts in the several figures.

The present invention relates to the heating of tools and is disclosed by way of illustration as embodied in a burnishing machine 15 for setting the sole edges of boots and shoes.

Machines for burnishing sole edges, commonly known as "edge setters", are generally provided with a moving tool profile to the sole edge desired and moved rapidly over 20 the sole edge in order to burnish it. For the performance of good work it is necessary to heat these tools to a relatively high temperature, for example, to a temperature of approximately 375° F. The most common means for heating the tools is a gas 25 flame. It has as a practical matter been necessary to use a luminous and therefore a smoky gas flame for two reasons principally: In the first place, a blue flame form 30 a Bunsen burner is so nearly invisible that the operator is liable to injure himself with it, and in the second place, it has proved very difficult as a practical matter to keep a very small blue flame alive in a shoe factory operating room. A smoky flame, on the 35 other hand, deposits soot on the tool and more or less damage to the shoe results.

It has been proposed to use electricity for heating edge setting tools because of 40 its convenience in use and the absolute cleanliness obtainable by its use. Several difficulties have interfered with the universal commercial acceptance of this heating agent. For example, if a resistance 45 heating unit is suspended upon the moving tool carrier, the conveyance of the current to and from the unit involves a difficult matter of design and the unit itself and its connections are in continual danger due to the 50 rapid movement of the parts containing them. If the unit is suspended upon a fixed part of the frame, it is very difficult to convey heat enough to the tool with any degree whatever of economy in consumption of electric 55 energy.

It is a principal object of my invention to provide for the electric heating of tools in a manner which shall not be subject to the above described and other disadvantages. In carrying out my invention, I have provided for heating the tools by a blast of electrically heated gas, preferably air. In this way, all the advantages of electric heating are retained and none of the disadvantages are encountered since the electric 60 unit can be mounted upon the stationary frame of the machine and therefore involves no troublesome or expensive designing, and the air heated by it can be conveyed from a small pipe to the vicinity of the tool with 65 all the convenience of any gas flame construction. In this aspect of it, an important feature of the invention is, therefore, a novel organization of burnishing means and electrical heating means comprising an 70 electrical unit arranged to heat a current of gas which is conveyed to the tool.

Another important feature of the invention by which a very considerable economy in the use of electric energy is effected consists in producing an initial rise in temperature of the air by using the air in the room as a heating agent and thus introducing the air to the unit at a substantially higher 80 temperature than would have been possible 85 if it had been taken directly from the supply pipe. I found that a substantial pressure in the air supply was necessary in order to keep the stream of hot air moving satisfactorily, this air stream being of small 90 cross-section and consequently subject to considerable skin friction in the pipe which carried it. When this air under pressure was permitted to expand in the vicinity of the electric unit, its temperature immediately 95 dropped 20 to 30 degrees because the expansion was substantially adiabatic. The air was then warmed by its passage over the unit. I found that by allowing the air 100 to expand in a coil in thermal communication with the air of the room its temperature would be raised substantially to the room temperature in passing through the coil and that if it were then introduced to the electric unit, the same unit would produce a delivery temperature some 25 or 30 105 degrees F. higher than if the air were expanded directly into the unit chamber. In this aspect of the invention I produce what is virtually isothermal expansion independ- 110

ently of the heat unit, and in the embodiment illustrated I effect this by expanding the air into a chamber in thermal communication with the surrounding air. A substantially smaller unit can therefore be used in heating a given volume of air per minute to a given temperature by virtue of this feature of the invention, in accordance with which I have provided a supply of air under substantial pressure, means for effecting substantially isothermal expansion of the air, and means for heating the air. The machine shown provides a receptacle in which the air may be expanded to the operating pressure in good thermal communication with the surrounding air and means for conveying the air from the receptacle into thermal communication with an electric unit.

I have also provided a novel means of conveying the heated air directly to the tool. The machine shown discloses an oscillating head carrying a plurality of edge setting tools, a shank iron and a forepart iron. As is well known, it is customary to mount these tools side by side upon a single axis and to turn the axis in order to interchange the tools in operative position so that the operator may use one after the other in setting the sole edge. I have provided a tool carrying head having a conduit for conveying the air directly to the tool into which conduit the air may be conveyed from the electric unit. In the machine shown each tool is provided with an individual conduit, the receiving end of which is brought into communication with the outlet from the unit chamber as the tool is brought into operative position. Such structure is an important feature of the invention. The structure described has another very important advantage which is that the tool supplying conduit is heated by the passage of the air through it and conducts heat through the tool mounting to the tool. The tool therefore acquires heat from the air both by conduction and by convection. This arrangement secures a very important and considerable economy in the expenditure of electrical energy over any system involving the mere blowing of the hot air against the tool from a nozzle analogous to the gas flame construction.

The drawing shows a side view of an edge setting machine embodying the invention. The pulley 10, driven by the belt 12, through mechanism in a casing 14 designed to transform movement of rotation into movement of oscillation, oscillates the shaft 16 in the bearings 17 carrying the head 18. The mechanism in the casing 14 may be of any desired type, for instance, such as is shown in my Patent 1,268,832, June 11, 1918. The head 18 is provided with a tool carrier 20 arranged to carry two tools 22 and 24. The tool head 20 may be rotated 180° in

order to interchange the tools in operative position by any desired means, preferably by the means shown in my application Ser. No. 93,912, filed Apr. 27, 1916, to which reference may be made. The interchanging means, broadly speaking, comprises a lever 26 operated by pushing the shoe in the hand of the operator against its end at 28, the said lever carrying a threaded screw-driver blade 30 engaging in a slot 32 when the lever is operated. The screw-threads on the blade 30 rotate the blade and the head 20. The specific tool interchanging means constitutes no part of the present invention and need not be further described.

The tool head 20 carries two sleeves 34 and 36 which receive spindles mounted on the tools 22 and 24. These spindles are notched, and springs 38 projecting through holes 40 in the sleeves engage the notches and hold the tools in position. Fastened integrally to the sleeves 34 and 36 are two little conduits 42 and 44, respectively, open at the top, extending downwardly parallel to the tool spindles, and curved around to open directly against the tools. Heated air introduced into the upper ends of the conduits will therefore pass through them and blow against the tools, giving up heat meanwhile to the conduit walls which conduct it through the sleeves 34 and 36 to the tools. The tools are thus heated both by conduction and convection, and every economic use is made of the heat content of the air. The two conduits are symmetrically arranged relatively to the axis of the tool holder 20. Therefore the conduit appurtenant to the tool in use at any given time (the right hand tool as shown in the drawing) will always be in the position occupied by the conduit 44 in the drawing. Mounted upon the main frame of the machine is a heat insulating casing 46 enclosing a coil 48 which in turn encloses, in the construction shown, an electric unit 50. One end of the coil 48 exhausts through a pipe 52 arranged with its end directly over and in close relation to the upper end of the conduit appurtenant to the tool operating at any given time. The other end of the coil communicates with a coil 54 of any desired length the other end of which communicates through a valve 56 with a pipe 58 carrying air under any desired pressure. I have found that the ordinary compressed air system of a factory constitutes a suitable source of air supply. The air in expanding through the valves 56 flows into the coil 54 where the drop in temperature resulting from the nearly adiabatic expansion is made up by absorption of heat from the surrounding air. It then passes into the coil 48 which surrounds the unit 50. On emerging into the pipe 52 it is heated to a temperature of, for example, 375 to 400 degrees Fahrenheit. The

end of the pipe 52 registers with the end of the conduit appurtenant to the operating tool and the air, as it passes through the conduit, blows out upon the tool and also heats the sleeve and tool by conducted heat as described above. The stroke of the tool is, in machines of this type perhaps $\frac{1}{4}$ inch, and the upper end of the conduit is of sufficient spread to register with the end of the pipe 52, whatever the position of the tool in its swing.

The heated air is directed against that lateral face of the tool farthest from the operator, who holds the shoe upper toward him as he sets the sole edge. The heated air thus blows out parallel to the tread face of the sole, does not contact with it sufficiently to affect its temperature injuriously, and does not reach the rest of the work at all. This feature of the invention is of importance in connection with lowering the temperature of a tool by a cold blast as well as raising it as herein shown.

The machine contains a finger hook 60 which is hollow and is provided with the ordinary gas burner 62 which may be used if electrical energy is not obtainable. For further description of the finger hook shown, reference may be made to my application Ser. No. 93,912, above referred to, as the said hook forms no part of the present invention. It will be noticed that the conduits 42 and 44 are arranged above the tools which they heat rather than below them, and are therefore entirely out of the way of the operator in manipulating the shoe, the tools and the finger hook.

Having described my invention, what I claim as new and desire to secure by Letters Patent of the United States is:—

1. In a machine of the class described, a tool, a gas casing, an electric unit arranged to heat the gas in said casing, means for supplying gas to the casing, and means for conveying the heated gas from the casing to the tool in order to heat the tool, constructed and arranged to protect the work from direct contact with the heated gas.

2. In a machine of the class described, a tool, a source of compressed gas, means for effecting substantially isothermal expansion of the gas, and means for heating the isothermally expanded gas and conveying it to the tool.

3. In a machine of the class described, a tool, a source of compressed gas, means for effecting substantially isothermal expansion of the gas, and independent means for heating the isothermally expanded gas and conveying it to the tool.

4. In a machine of the class described, a tool, a source of compressed air, means for effecting substantially isothermal expansion of the air from the source, an electric unit, means for bringing the air in contact with

the unit to heat the air, and means for conveying the heated air to the tool.

5. In a machine of the class described, a source of compressed air, an expansion chamber for the air in thermal communication with the air of the room, a heating coil communicating with said chamber, means for heating the coil, and a pipe arranged to conduct air from the coil to the tool.

6. In a machine of the class described, a tool, a channel adjacent to the tool having its walls in thermal communication with the tool, said channel also having an opening opposite the tool whereby heated air passing through the channel will communicate heat to the tool by both convection and conduction, and means for forcing heated air through the channel.

7. In a machine of the class described, a tool carrier, a plurality of tools mounted thereon, a channel in thermal communication with each tool, mechanism for interchanging the tools to facilitate the performance of different operations at the same operative position, an air pipe having its end registering with the end of the channel appurtenant to the tool in operative position, and means for forcing heated air through the pipe.

8. In a machine of the class described, a tool carrier, a rotatable spindle in the carrier, a plurality of tools mounted on the spindle, a conduit mounted on the spindle appurtenant to each tool, said tools and conduits being symmetrical relatively to the axis of the spindle, said spindle being rotatable to present different tools in operative position, and a pipe arranged to deliver heated air into the conduit appurtenant to the tool in operative position.

9. In a machine of the class described, a tool carrier, a tool mounted on the carrier, a conduit embedded in the carrier having an opening opposite the tool, and means for supplying heated air to the conduit whereby the heated air will be forced against the tool through the opening and will also communicate heat to the tool by conduction through the walls of the conduit.

10. That improvement in the art of heating tools which consists in taking air from a source of compressed air, substantially isothermally expanding the air, heating the isothermally expanded air to operating temperature, and applying it to the tool.

11. That improvement in the art of heating tools which consists in expanding the air from a source of compressed air, supplying heat to correct the drop in temperature due to adiabatic expansion, heating the air to operating temperature, and applying it to the tool.

12. In an edge setting machine, a rotatable spindle, a head at the lower end thereof, a tool carrying holder at the lower end of

the spindle, an edge setting iron carried by said holder, and a conduit mounted on the holder and extending downwardly to a point opposite the iron in such manner that it lies entirely above the space in which the operator manipulates the shoe, arranged to convey heated air to the iron.

13. In a machine of the class described, a tool, a source of compressed gas, a receptacle for permitting expansion of the gas having provision for replacement of heat lost by the gas in adiabatic expansion, a casing for receiving the reheated gas, and containing an electric unit constructed and arranged to raise the reheated gas to the desired temperature, and means for conveying the gas from the casing to the tool.

14. That improvement in the art of heating tools which consists in taking air from a source of compressed air, expanding the

air, allowing the expanded air to absorb a substantial quantity of heat from the atmosphere to raise its temperature after the drop due to the expansion, heating the expanded and warmed air to operating temperature, and applying it to the tool.

15. In a machine of the class described, a source of compressed air, an expansion chamber for the gas in thermal communication with its surroundings whereby the gas may absorb heat from its surroundings to offset the drop in temperature due to expansion, a heating chamber constructed and arranged to heat the expanded and warmed gas to operating temperature, and means for conducting the gas to the tool.

In testimony whereof I have signed my name to this specification.

FREDERICK M. FURBER.
